SPRING HINGE

Edwin G. Hempel, Cranston, R. I.

Application June 29, 1939, Serial No. 281,794

12 Claims. (Cl. 16—182)

This invention relates to hinges for boxes and containers provided with covers and for other purposes, and refers particularly to leaf hinges having one leaf provided with resilient portions serving as springs while lugs upon the other leaf coat with said springs to determine a closed position of the cover as well as an open position thereof.

The main object of my invention is to produce a box and cover hinge which can either be molded into the box proper and cover or introduced into the same after the box and cover have been molded.

Another object is to have a hinge which can be made easily at a low figure and yet is durable and effective in use.

A further object is to have a hinge of the character indicated in which it is not necessary to insert any form of spring or resilient means in order to cause the hinge to resiliently maintain an open and a closed position of the cover on the box.

It is also an object of this invention to have one leaf of the hinge slotted so as to leave two resilient wings in camming contact with camming lugs upon the other leaf in order to determine resiliently maintained positions of the hinge in open and closed positions.

It is likewise an object to reinforce or stiffen an intermediate portion of the leaf of the hinge which is slotted so that the resilience of the slotted leaf will be very powerful and effective.

It should be mentioned that it is even an object to have the hinge so constructed that collapsible or telescopic pins can be applied to the hinge in order to assemble the hinge when the members thereof are already inserted or molded into the box and cover.

Further objects and the various advantages of my invention will appear more fully hereinafter as this specification proceeds.

In the accompanying drawings forming part hereof, and intended to facilitate clear comprehension of my invention:

45 Figure 1 is a perspective view of a box or container with a cover hinged thereto by means of hinges embodying certain features of the present invention;

50 Figure 2 is a perspective view of one hinge in exploded relation to a recess of the box;

Figure 3 is an inverted rear view of the same hinge shown in Figures 1 and 2;

Figure 4 is a fragmentary section of Figure 1 through one of the hinges as taken on line 4—4;

55 Figure 5 is a horizontal fragmentary section

of the rear wall of the box showing the rear portion of one hinge;

Figure 6 is a section of the parts shown in Figure 5 and taken on line 6—6;

Figure 7 is a perspective resembling that of Figure 3 and showing a modification of the hinge;

Figure 8 is a fragmentary section similar to Figure 4 but illustrating the use of the modification of Figure 7;

Figure 9 is a fragmentary view of the rear portion of a box and related portion of a cover wherein the hinge is almost completely embedded in the material composing the box and cover, portions being torn away to disclose the main features of the hinge;

Figure 10 is a fragmentary enlarged section of the hinge embodying the invention showing a camming lug of one of the hinge members and the cooperating resilient leaf portion of the other member.

Throughout the views same reference numerals indicate the same or like parts.

In the practice of my invention, a box generally indicated by 1 has a cover generally indicated by 2, these members being preferably made of plastic material or die cast metal and being particularly intended to be conventional or of any useful shape as the box and its cover per se do not actually form essential parts of the present invention so that said members as shown in Figure 1 are not intended to form any limitation as to the use and location of the hinge of the invention herein.

Thus, the rear wall 3 of the box has one or more reinforcements 5, 5 which is also true of the rear wall 6 of the cover, the latter having reinforcements 7, 7 to strengthen the box and cover and adapt the same to have hinges molded or inserted to said reinforcements without weakening the structures involved. The reinforcement 5 in each case has an open slot 8 and in the rear of said slot are a pair of extensions or recesses 9, 9, while each reinforcement 7 of the cover has a similar slot 10 which is also widened at the rear portion of the cover to form recesses 11, 11. The presence of the reinforcements is not essential but is merely a manufacturing precaution which can, in many cases, be modified or omitted so that the open slots 8 and 10 and the recesses 9 and 11 can be formed in the rear slots 3 and 6 of the box and cover if so desired. In the slots 8 and 10 may be inserted the two leaves 12 and 13 respectively of a hinge which is retained in assembled condition by means of a hinge pin 14 which extends through the end lugs 55

15 and 16 of leaf 12 and lugs 17 and 18 of leaf 13 of the hinge. The hinge leaf 12 is bent at both ends and provided with retaining lugs 19, 20 adapted to be inserted into recesses 9, 9 and slot 8 in the rear wall 3 of the box, while hinge leaf 13 has a pair of similar retaining lugs 21, 22 adapted to be inserted into recesses 11, 11 of slot 10 in the rear wall 6 of the cover, such insertion naturally occurring from the edges of the 10 rear walls 3 and 6 of the box and cover respectively along the planes thereof.

In order to fasten the hinge in place, several expedients are possible, the first being to wedge the hinge leaves in place in a similar fashion to that used in the resilient hinge of my pending application, Serial No. 274,168 filed May 17, 1939. In other words, the leaf 12 may be furnished upon its free end with a bent-up portion 23 terminating at both ends somewhat adjacent to retaining lugs 19 and 20 in wedging members 24, 25 while hinge leaf 13 has a similar bent-up portion 26 terminating at the ends in wedging members 27, 28 adapted to be forced down and wedged against the end walls 29 and 30 of the open slot 8, wedging members 24 and 25 wedging against the ends 29' and 30' in each of the slots 10 in the cover wall 6. Obviously, when the wedging members have been forced down more nearly in line with portion 26 as indicated in Figures 4, 5 and 6 and similarly when the lugs 24 and 25 have been forced into the cover almost in line with portion 23, these four lugs will wedge so sharply in the slots of the rear walls of the box and cover that the hinge members are no longer removable but firmly wedged in place.

It is not intended to apply a loose spring to the hinge in order to have the same capable of retaining the cover in erect position as shown in Figure 1 or in closed position, but instead the construction of the hinge is itself so designed that this desirable effect will occur. Thus, the hinge leaf 12 has a pair of slots 31 and 32 running inwardly toward the center of the leaf from the edges thereof starting approximately at the inner end of each of retaining lugs 19 and 20 so as to produce a pair of resilient portions 33 and 34 which are stiffened by an indentation forming a reinforcement 35 in the intermediate portion of said hinge leaf. The lugs 17 and 18 of hinge leaf 13 engage against the inner flat faces of resilient portions 33 and 34 and serve as camming lugs so that variations in the profile of each lug will tend to displace said resilient portions slightly out of plane with the main body portion of leaf 12. If then each lug has a flat edge 36 (Figure 10), the hinge leaf 13 will tend to come to rest in the position indicated in broken lines at 13' with the flat edge 36 disposed against resilient portion 34 of leaf 12 as indicated in broken lines at 36' but when the hinge leaves are brought practically into alignment the slightly inclined edge 37 will tend to allow resilient portion 34 to descend toward hinge pin 14 so as to retain the hinge members in said position which actually represents a closed position of the cover on the box. Of course, the edge 36 can be slightly inclined so as to tend to change the angle of 70 13' with respect to leaf 12 to determine an open position of the cover but this angle is optional and is merely indicated as approximately 90° with respect to leaf 12 in Figure 10 and is only intended to represent that the hinge leaves occupy positions corresponding to any predetermined

open position of the box cover with respect to the box.

In the form of hinge already described, a long hinge pin 14 may be used as shown or short rivets or studs limited to the lugs at each end may be used.

In Figure 7 a modification of the hinge consists mainly of two leaf members 38 and 39 which do not have any wedging members or lugs similar to 27 and 28 of leaf 13 for example, but the hinge 10 lugs 15', 16', 17' and 18' correspond in all details to the hinge lugs 15, 16, 17 and 18 already described, while the retaining lugs 19', 20', 21' and 22' serve to anchor the hinge leaves in place in somewhat the same manner as retaining lugs 15, 16, 20, 21 and 22, as described. In addition, the slots 31' and 32' in leaf 38 serve the same purpose as the slots 31, 32 in previously described hinge leaf 12 with a result that portions 33' and 34' are resilient so as to serve as springs against 20 which the camming lugs 17', 18' engage in order to determine definite open and closed positions of the hinge parts and the cover which is thereby connected to the box.

On the other hand, this form of hinge as particularly shown in perspective in Figure 7, is intended to be molded in place and for this reason apertures 40, 41, 42 and 43 are preferably made in the leaves so that a material of the box and cover can extend through these apertures and 30 terminate flush at 44 and 45 for example, with the exposed surfaces of the hinge leaves 38 and 39 while the retaining lugs 19' through 22' are embedded in the material forming the rear walls 46 and 47 of the box 48 and cover 49 respectively. In this form, the indented reinforcement 4 in leaf 38 is similar to reinforcement 35 previously described. Due to the fact that the retaining lugs 19' through 22' are thus embedded and altogether out of sight and also that the plastic or die cast metal extend through the aperture at 44 or 45 as mentioned, no wedging members or other means will be required to hold the hinge members in place. Obviously, the two hinge leaves are separately molded into the box 45 and cover and are only assembled after the molding of these parts has been completed. For this reason, the hinge pins used for such hinge must be inserted when assembling the cover with the box which is actually performed by assembling 50 the hinges rigidly secured in the rear walls of the box and these hinge pins are preferably made telescoping or expandable as in the case of pin 50 shown in Figure 7. This pin consists of two aligned pin members 51 and 52 having a yielding curved portion 53 connecting these two parts, this construction making it possible to draw the two pin portions 51 and 52 toward each other sufficiently to be inserted between lugs 17' and 18' and thereafter forced apart so that the ends 60 of said pin will pass through these lugs and into lugs 15' and 16'.

A modified manner of molding in the hinge of Figures 7 and 8 is shown in Figure 9 wherein the hinge leaves 38 and 39 are partly embedded 65 in the rear walls 54 and 55 of a box and cover respectively, so that the material of said rear walls passes entirely through the apertures 40 to 43 and the retaining lugs 19' through 22' are completely embedded in said walls as in the case 70 of the box and cover of Figure 8. In this case, a slight play space is allowed in the material of the box wall 54 for the resilient portions 33' and 34' so that the resilient spring effect will be had even in this case. It is clear that the expandable pin 50 of Figure 7 is not the only construction 75

possible for a hinge pin which is to be expanded into the lugs at the ends, and hence, in Figure 9 a telescoping pin is shown which consists of a tubular member 56 having end pins 57 and 58 expanded into the lugs 15' through 18' by a spring 59. Other constructions of expandible or telescoping pins may be resorted to so long as they make it possible to assemble the hinge members after being molded in place upon the box and covers which are to be assembled subsequently to the molding thereof, the hinge parts being preferably of metal.

From the foregoing, it is evident that a resiliently operating hinge is capable of determining at least one open and definitely closed position of a cover on a box without the use of extraneous or inserted springs while the side hinge may either be inserted as an assembled hinge into the box and also the cover so as to assemble the latter thereto or may be molded separately in the rear portions of the box and cover and thereafter assembled, and in every case operating in the same manner.

Manifestly, other variations may be resorted to and parts used without others or replaced by equivalents within the scope of the appended claims.

Having now fully described my invention, I claim:

1. A spring hinge for a box and cover, comprising two hinge leaves individually adapted to be secured to or embedded in the rear portions of said box and cover, each hinge leaf consisting of a substantially flat metal plate which is bent down at two opposite ends thereof to form rigid end portions having anchoring flanges extending therefrom in general parallelism with the plate, there being hinging means at least at the corners of one edge of each of said hinge leaves for receiving a hinge pin, and a hinge pin means of alterable length serving to engage with the hinging means in order to connect the two hinge leaves, the anchoring flanges adapting said hinge leaves to be embedded in the rear walls of the box and cover when making the latter and said hinge pin means adapting the box and cover for assemblage by insertion and subsequent longitudinal extension of said hinge pin means in said hinging means, there being also resilient means upon the hinge tending to determine an open and a closed position of the cover on said box.

2. A hinge according to claim 1, wherein at least one of the hinge leaves has open areas in the flat portion thereof serving to increase the anchorage of the same in the portion in which it is embedded.

3. A spring hinge for a box and cover, comprising two hinge leaves individually adapted to be secured to the rear portions of said box and cover, hinge pin means pivotally connecting said hinge leaves together, at least one slotted portion in one of the hinge leaves starting diagonally inwardly from an end thereof toward the central area of the same causing a resulting portion of the same to be resiliently yieldable out of the general plane of the rest of the leaf involved, and camming means projecting rigidly from the other of said hinge leaves adjacent to said hinge pin means toward and cooperating with said resulting portion so as to determine at least one mutually aligned position of said hinge leaves which corresponds to a closed position of the cover on the box.

4. A spring hinge for a box and cover, comprising

two hinge leaves individually adapted to be secured to the rear portions of said box and cover, hinge pin means pivotally connecting said hinge leaves together, at least two slotted portions starting inwardly from two opposite edges of said one of the hinge leaves so that two resulting portions thereof will be resiliently displaceable out of the general plane of the same, and plural camming means projecting from the other of said hinge leaves toward and cooperating individually with said resulting portions so as to determine at least one mutually aligned position of said hinge leaves which corresponds to a closed position of the cover on the box.

5. A spring hinge for a box and cover, comprising two hinge leaves individually adapted to be secured to the rear portions of said box and cover, hinge pin means pivotally connecting said hinge leaves together, retaining members upon the opposite ends of both hinge leaves serving to retain the same in assembled relation with respect to said rear portions of the box and cover, at least one slotted portion in one of the hinge leaves starting inwardly from one of said ends causing a resulting portion of said one of the hinge leaves to be resiliently displaceable from the general plane of the rest of the hinge leaf involved, hinge lugs projecting from the retaining members upon both leaves and a camming portion upon at least one of the hinge lugs of the other of said hinge leaves disposed against and cooperating with said resulting portion upon said one of the hinge leaves, so as to determine at least one mutually aligned position of said hinge leaves which corresponds to a closed position of the cover on the box.

6. A spring hinge for a box and cover, comprising two hinge leaves individually adapted to be secured to the rear portions of said box and cover, hinge pin means pivotally connecting said hinge leaves together, retaining members upon the opposite ends of both hinge leaves serving to retain the same in assembled relation with respect to said rear portions of the box and cover, separate slotted portions starting inwardly from the two opposite ends of one of the hinge leaves, hinge lugs projecting upon the retaining members of both hinge leaves and camming portions upon the end lugs of the other of said hinge leaves engaging against and cooperating with the resulting resilient portions upon said one of the leaves so as to determine a mutually angular position of both hinge leaves corresponding to an open position of the cover on the box and a mutually aligned position of said hinge leaves which corresponds to a closed position of the cover on the box.

7. A spring hinge for a box and cover, comprising two hinge leaves individually adapted to be secured to the rear portions of said box and cover, hinge pin means pivotally connecting said hinge leaves together, each hinge leaf consisting of a generally plane metal plate which is bent down at two opposite ends thereof to form rigid end portions having flanges extending therefrom in general parallelism with the plate, a hinge lug projecting upon each bent down end portion of each hinge leaf, the plate of one of the leaves having inwardly directed slotted portions commencing at the ends of the leaf adjacent to the bent down portions upon said leaf so as to form resulting resilient portions adjacent the hinge lugs of the same leaf, cam portions upon the hinge lugs of the other hinge leaf engaging against said resulting resilient lug portions of the

first hinge leaf so as to cooperate therewith and determine a plurality of mutually different angular positions of said hinge leaves with respect to each other to correspond to a closed position 5 and one or more open positions of the cover with respect to the box.

8. A spring hinge for a box and cover, comprising two hinge leaves individually adapted to be secured to the rear portions of said box and cover, hinge pin means pivotally connecting said hinge leaves together, each hinge leaf consisting of a generally plane metal plate which is bent down at two opposite ends thereof to form rigid end portions having flanges extending therefrom in general parallelism with the plate, a hinge lug projecting upon each bent down end portion of each hinge leaf, the plate of one of the leaves having inwardly directed slotted portions commencing at the ends of the leaf adjacent to the bent down portions upon said leaf so as to form resulting resilient portions adjacent the hinge lugs of the same leaf, reinforcing means stiffening the plate portion of said hinge leaf so as to stiffen and reinforce the resiliency 20 of the resulting portions of said leaf, cam portions upon the hinge lugs of the other hinge leaf engaging against said resulting resilient lug portions of the first hinge leaf so as to cooperate therewith and determine a plurality of mutually different angular positions of said hinge leaves with respect to each other to correspond to a closed position and one or more open positions of the cover with respect to the box.

9. A spring hinge for a box and cover according to claim 1, which is capable of being assembled when the hinge leaves are already in place in a box and cover and in which for this purpose the hinge pin means includes a pair of substan-

tially aligned pin portions spaced apart and an integral yielding adjustable portion between the adjacent ends of said pin members comprising an alterable member connecting said inner ends and capable of being altered in length, so as to allow the hinge leaves to be assembled by insertion of said aligned pin portions from within the outline of the hinge as a whole. 5

10. A spring hinge for a box and cover, comprising two hinge leaves individually adapted to be secured to the rear portions of said box and cover, hinge pin means pivotally connecting said hinge leaves together, two slotted portions extending limited distances inwardly from two edges of one of said hinge leaves so that two resulting integral portions thereof will be resiliently displaceable out of the general plane of the same, and plural camming means projecting from the other of said hinge leaves toward and co-operating individually with said resulting portions so as to determine at least one mutually aligned position of said hinge leaves which corresponds to a closed position of the cover on the box. 15

11. A spring hinge for a box and cover according to claim 1, in which the hinge pin means comprises a telescoping pin structure which is capable of being contracted or extended in length for initial insertion and subsequent retention in the hinge. 20

12. A spring hinge for a box and cover according to claim 1, in which the hinge pin means comprises an elongated cylindrical pin structure which is capable of being axially altered in length 35 for initial insertion and subsequent retention in the hinge.

EDWIN G. HEMPEL.
